ELBERT S. DODGE, OF ILION, NEW YORK, ASSIGNOR TO REMINGTON TYPEWRITER COMPANY, OF ILION, NEW YORK, A CORPORATION OF NEW YORK.

TYPEWRITING-MACHINE.

1,330,063.

Specification of Letters Patent.

Patented Feb. 10, 1920.

Application filed May 29, 1919. Serial No. 300,611.

To all whom it may concern:

Be it known that I, ELBERT S. DODGE, citizen of the United States, and resident of Ilion, in the county of Herkimer and State 5 of New York, have invented certain new and useful Improvements in Typewriting-Machines, of which the following is a specification.

My invention relates to typewriting and 10 like machines, and more particularly to the type actions of such machines.

The present invention is directed to type 15 actions having members thereof operably connected by a pin working in a slot, and one object of the invention is to produce a superior connection and one in which the walls of the slot present smooth surfaces for coöperation with the pin which slides in said slot and on the walls thereof.

20 A further object is to provide means in said pin-and-slot connection to facilitate the adjustment of the type action after it is assembled.

To the above and other ends which will 25 hereinafter appear, my invention consists in the features of construction, arrangements of parts, and combinations of devices to be hereinafter described and claimed.

In the accompanying drawings, wherein 30 like reference characters indicate corresponding parts in the different views.

Figure 1 is a detail fragmentary side elevation of a center type action embodying my invention.

35 Fig. 2 is an enlarged detail fragmentary side view showing the heel of a type bar and the upper end of its co-acting sub-lever, the head of the connecting pin being sectioned away.

40 Fig. 3 is an enlarged detail fragmentary side view of a type bar, with the finishing tool and showing the tool introduced into the opening leading to the slot.

Fig. 4 is a view corresponding to Fig. 3 45 but showing the parts as they appear at the limit of movement of the tool along the slot in one direction, the tool being shown in cross section taken through the scraping edges.

50 Fig. 5 is an enlarged detail fragmentary sectional view of the type bar and tool, the section being taken lengthwise of the slot

and with the tool shown about midway in its line of movement.

Fig. 6 is an enlarged detail transverse 55 sectional view of the same.

Fig. 7 is a detail perspective view of the finishing tool.

In the accompanying drawings I have shown only so much of a front strike type-writing machine as may be necessary to arrive at an understanding of my invention. I have also shown the tool employed in finishing parts of the type action.

The type action shown in the present instance comprises a key lever 1 fulcrumed at 2 in the base 3 of the machine and provided with a finger key 4 and a returning spring 5. An upwardly extending arm 6 on the key lever carries a laterally projecting pin 7 which is received in a slot 8 formed in the forward projecting arm of an angular sub-lever or actuating member 9 fulcrumed at 10 to a cross bar 11 secured to the base of the machine. An upwardly extending arm 75 of the sub-lever carries a laterally projecting pin 12 formed with a head 13 and a cylindrical, or substantially cylindrical, stem or body portion. This pin extends through a slot in its associated or co-acting member 80 which, in the present instance, is a type bar 14 pivoted at 15 to a slotted type bar segment 16, the bar normally resting against a type bar rest or pad 17. The heel of the type bar is perforated to produce a slot 18, 85 having parallel sides or walls 19, and it is in this slot and against these walls that the pin 12 works. At its end nearest the pivot 15, the slot 18 communicates with a hole 21, the diameter of which is greater than the width of slot 18, and resulting in shoulders 20 at which the walls 19 terminate abruptly. At its other end, the slot 18 communicates with a cross-slot 23, producing shoulders or reentrant angles 22 90 at which the other ends of the walls 19 abruptly terminate. Said cross-slot 23 is of a length cross-wise of slot 18 greater than the width of said slot 18 and projects beyond it in both directions, as shown. Said cross-slot is of a width less than the diameter of pin 12, so that said pin cannot get caught on the shoulders 22, and preferably, as shown in the drawing, said slot 23

is of a width less than one-half the diameter of pin 12, so that said pin cannot get on said shoulders at all.

Upon the depression of a finger key the 5 associated type bar will be moved from its normal position to the printing position indicated in dotted lines, and during such movement of the parts the pin 12 will slide back and forth along the slot between and 10 on the walls 19 thereof, effecting a movement of the bar in the usual manner.

It will be understood that the size and shape of the enlarged opening 21 is such that the head of the pin 12 may be introduced through said opening to assemble the parts, but that in the operation of the parts the pin will always remain within the slot 18 and in a position to co-act with the parallel walls 19 thereof. In practice I prefer to 20 have the pin normally seated near the lower end of the slot, as shown in Figs. 1 and 2, and say about $1\frac{1}{64}$ of an inch from the bottom wall 24 of the slot.

The pin 12 is usually made of a diameter 25 slightly less than the distance between the walls 19 of the slot, say about $8\frac{1}{1000}$ of an inch. It is desirable to have the pin normally bear against the upper wall 19 of the slot, as shown in Fig. 2, so that there may 30 be no lost motion between the upper wall and the pin when the type bar is at rest. As a result, when the parts return to normal position after each actuation the pin will always co-act with the upper wall 19 35 of the slot and tend to prevent any rebound of the type bar from the pad or rest 17.

In operation the pin 12 bears on the walls 19 of the slot, sliding back and forth along said slot, and it is highly important that 40 this distance between the walls be accurate and that the contact faces of the walls present a smooth and even surface for co-operation with the pin, to provide an easy acting type action. To this end I subject the type 45 bar to a special treatment which will now be described. Each sheet metal bar is punched or stamped out and the slot 18 and enlarged openings 21 and 23, as shown in Fig. 3, are punched therein. This leaves 50 the walls of the slot 18 in a relatively rough state with markings or scratches, which extend transversely of the walls and also leaves slight burs at the edges or corners of the walls caused by punching out the slot. I 55 have not attempted in the drawings to show this relatively roughened state of the walls of the slot, nor the slight burs which appear after punching the slot in the bar, but they may be assumed to be present in the 60 type bar shown in Fig. 3. In order to remove this roughness of surface and present a superior surface on the walls 19 of the slot, I employ a finishing tool, preferably of the character shown in detail in Fig. 7 and 65 which is designated as a whole by the ref-

erence numeral 25. This tool consists of a rod or bar having two working edges 26 on opposite sides thereof, said edges having a concave curvature in a plane perpendicular to the slot 18, as best indicated in Figs. 6 70 and 7, in order to give a convex curvature to the walls 19, as best shown in Fig. 6. This operation also effectively removes any burs that may be along the corners of the walls and also enables the pin 12 thereafter 75 to co-operate more effectively with the walls of the slot without cramping or binding, as will hereinafter more clearly appear. The tool may be formed by making four milling cuts therein, two on each side thereof. This 80 results in a working edge 26 being formed on each side, leaving a bevel or slope 26 which extends away from the working edge on both sides thereof.

The width of the tool, measured from one 85 edge 26 to the other, is somewhat less than the width of the slot 18 (Figs. 4 and 6), although the body and upper end portions of the tool are of greater diameter or width 90 than said slot.

The tool is used as follows: It is first inserted into the opening 21, as shown in Fig. 3, and it is then moved rectilinearly back and forth against one of the walls 19 of the slot until that wall is finished, thus 95 smoothing the surface longitudinally of the slot or in a direction at right angles to the direction in which the roughness is produced by the punching operation. In this 100 operation the tool is pressed rather lightly against the wall 19 and it requires a number of reciprocations of the tool to bring the surface of the slot to the desired shape and smoothness. After one wall is finished pressure is applied in the opposite direction 105 and the tool is reciprocated against the opposite wall until that wall is finished. In the reciprocating action of the tool I find that the results are influenced in an important respect by the abrupt ends 20 and 22 110 of each surface or wall 19, that is to say, by the fact that the slot communicates at its ends with the openings 21 and 23, so that each straight finished wall 19 terminates in a reentrant angle or free corner, or shoulder. The result is that the tool at each stroke 115 thereof runs entirely off of the surface or edge on which it is operating, so that the metal is not piled up at the end of each operating stroke of the tool but is removed 120 completely; that is to say, entirely to the end of the surface under treatment.

The shape of the tool can of course be varied but the preferred form is substantially as shown in the drawing. It will be 125 noted that the milling cuts 26 in the tool are concave in both directions, and in cross section as shown in Fig. 4, these cuts intersect in a sort of cusp at the edge 26. The edge 130 does not have the ordinary form of a

cutting tool such as is used in a planing machine but a form to produce a sort of scraping action, the metal of the type bar being removed, not in shavings but in a 5 sort of a powder, dust or in small particles, leaving a smooth surface.

It is of course desirable in the use of this tool that it be guided in its motion with sufficient precision and that a suitable 10 degree of pressure be applied to it. An automatic machine has been devised for this purpose. In the use of said machine it has been found that about 160 straight line movements of the tool suffices to finish one 15 side of the slot and the amount of metal removed from the walls of the slot 18 by the tool is sufficient to enlarge the width of the slot from $2/1000$ to $4/1000$ of an inch, the enlargement of about $2/1000$ of an inch 20 being found preferable.

It has been found in practice that my invention gives excellent results, producing a superior and highly satisfactory bearing surface on each of the walls of the slot 18, 25 said surfaces having the characteristics of bearing surfaces scraped smooth lengthwise, or in the direction of the sliding thereon of the pin 12.

The construction as herein shown also 30 possesses certain advantages in the assembling and adjustment of the machine. In practice, the key levers 1, sub-levers 9 and type bars 14, are all assembled before the type rest 17 is put in place, so that the 35 type bars all hang unsupported at their forward ends. Due to the weight of the type bars and to the tension of the springs 5, each type bar drops down at its forward end and the upright arm of its sub-lever 40 moves rearwardly until both are arrested by the pin 12 seating against the wall 24 of the cross slot 23, the type bar being then in an inclined position below the normal position which it will occupy when the 45 rest or basket 17 is placed in position. With all the type bars thus connected and positioned, the free ends thereof should describe a reasonably perfect arc of suitable standard radius, if the parts of the various actions and their connections are accurately 50 constructed and fitted. If, however, it be found that, due to inaccuracies of manufacture, one or more of the type bars drop materially below, or remain materially 55 above, such arc, then it is made evident that adjustment of those particular actions is required. It will be noted that under the conditions mentioned, all of the pins 12 occupy identical positions in their slots 18, that is to say, they are all in contact with the walls 24 of the cross-slots 23. If any type bar hangs too low, that 60 can be corrected by shortening the upright arm of the corresponding sub-lever 9; and if any type bar is too high, this can

be remedied by lengthening said upright arm. The sub-lever arm may be shortened by making two lateral bends in it in opposite directions, without moving the pin 12 to the right or to the left; and said arm may 70 be lengthened by a swaging operation with a suitable tool, such as a suitable pair of pliers; or in any of the customary ways practised by assemblers in this art. Only a slight adjustment of the arms carrying the 75 pins 12 is usually necessary to cure the defects and bring the type bars into alinement. A proper adjustment having been attained, the free ends of all the bars are elevated and supported in place on the type rest 17. As 80 a result thereof the pins 12 will no longer be seated against the walls 24 but each pin will be brought into proper relationship with its slot and with the walls 19 thereof, and all of them in substantially the same 85 relationship, and the parts are then ready to be operated. The degree or character of acceleration of the type bar afforded by the operation of the pin 12 in the slot 18, depends in part on the initial or normal 90 position of said pin along said slot, and by the described adjustment, this initial position and consequent initial leverage and acceleration are made substantially uniform 95 throughout the system of type actions.

By making the walls 19 of the slot convex as shown, cramping action is avoided between the walls of the slot and the pin when the upper end of a sub-lever and the heel of its associated type bar are not moved absolutely in parallel planes during the operation of the type action. This movement of the parts out of parallelism is apt to happen, more particularly in the side actions, and results in a change in the angular 100 relation of each pin 12 to the plane of the heel of its associated type bar. The convex surfaces of the walls 19 at this time prevent the pin from binding against the 105 walls of the slot.

What I claim as new and desire to secure by Letters Patent, is:—

1. In a type action, the combination of two coacting members, one having a slot and the other a pin which works in said slot, the slot communicating at one end with an opening of greater length crosswise of the slot than the width of the slot and of less width than the diameter of the pin.

2. In a type action, the combination of two coacting members, one having a slot and the other a pin which works in said slot the slot communicating at one end with an opening of greater length crosswise of the slot than the width of the slot and of a 125 width less than one-half the diameter of the pin.

3. In a type action, the combination of two coacting members, one having a laterally projecting pin and the other a slot with 130

- 4
- parallel convex side walls with which the pin coacts, each wall terminating abruptly at both ends in reentrant angles or shoulders.
5. A type bar having a slot therein for a pin whereby said type bar is operated, said slot having parallel walls or edges on which said pin bears, and communicating at both ends with openings whereby said bearing walls terminate in reentrant angles or shoulders, and said bearing walls having their surfaces scraped smooth lengthwise from one of said shoulders to the other.
5. A type action comprising a type bar having a slot therein and a sub-lever having a laterally projecting pin which slides in said slot, the slot communicating at each end with an enlarged opening of greater width than the width of said slot, each enlarged opening extending laterally of said slot at both sides thereof, substantially as and for the purposes specified.
6. A type bar having a slot to accommodate an operating pin and having also a connecting transverse slot the outer wall of which is adapted to bear against said pin so as to facilitate proper adjustment.
- Signed at Ilion, in the county of Herkimer, and State of New York this 21st day of May A. D. 1919.
- ELBERT S. DODGE.
